UNITED STATES PATENT OFFICE.

JAMES ROBERTS, OF BOSTON, MASSACHUSETTS, ASSIGNOR TO THE S. A. WOODS MACHINE COMPANY.

DESIGN FOR A CUTTER-HEAD HOOD FOR PLANERS.

SPECIFICATION forming part of Design No. 21,850, dated September 6, 1892.

Application filed August 4, 1892. Serial No. 442,185. Term of patent 14 years.

To all whom it may concern:

Be it known that I, JAMES ROBERTS, a citizen of the United States, residing at Boston, in the county of Suffolk, State of Massachusetts, have invented and produced a new and original Design for a Cutter-Head Hood for Planers and Matchers, of which the following is a specification, reference being had to the accompanying drawing, forming part thereof.

10 The drawing shows in perspective a cutter-head hood, showing my design.

The leading feature of the design for a cutter-head hood for planers and matchers having an irregular configuration consists of the 15 curved walls having wings A B and hollow projecting portions a b, the walls rising from

a curved base c, the edges a' b' of the wings A B being extended to the said base, the wings being bridged at top by a cover portion C, having its curved edge c' a continuation of the edges a' b'.

I claim—

The design for a cutter-head hood for planers and matchers, substantially as herein shown and described.

In testimony whereof I have signed my name to this specification in the presence of two subscribing witnesses.

JAMES ROBERTS.

Witnesses:

GEO. W. GREGORY,
JOHN C. EDWARDS.
